Inland Tarp & Liner Offers Custom-Made Temporary Storage Covers, available in inlandtarpandliner.com, announced Year 2018 [online], [site visited Apr. 19, 2022], Internet URL: <https://www.grainnet.com/reviews/grain-pile-covers> (Year: 2018).*

Primary Examiner — Kathleen L Jones*Assistant Examiner* — Jasmine L. Comedy(74) *Attorney, Agent, or Firm* — Goodhue, Coleman & Owens, P.C.(57) **CLAIM**

The ornamental design for fill under grain cover, as shown and described.

DESCRIPTION

FIG. 1 is a perspective view of a fill under grain cover showing our new design;

FIG. 2 is a front view thereof with the back view being a mirror image;

FIG. 3 is a left side view thereof with the right side view being a mirror image; and,

FIG. 4 is a top view thereof.

The broken lines in the Figures show portions of the fill under grain cover and environment which form no part of the claimed design.
